UNITED STATES PATENT OFFICE.

MAURICE E. BATES, OF KANSAS CITY, MISSOURI, ASSIGNOR TO BENJAMIN ELECTRIC MANUFACTURING COMPANY, OF CHICAGO, ILLINOIS, A CORPORATION OF ILLINOIS.

DESIGN FOR AN ELECTRIC-LIGHT CLUSTER.

No. 38,155.

Specification for Design.

Patented Aug. 7, 1906.

Application filed June 12, 1905. Serial No. 264,963. Term of patent 14 years.

To all whom it may concern:

Be it known that I, MAURICE E. BATES, a citizen of the United States, residing at Kansas City, in the county of Jackson and State of Missouri, have invented a new, original, and ornamental Design for Electric-Light Clusters, of which the following is a specification, reference being had to the accompanying drawings, forming a part thereof.

Figure 1 of the drawings is a perspective

view of my design for electric-light cluster. Fig. 2 is a bottom plan view of my electric-light cluster.

I claim—

The ornamental design for electric-light cluster, as shown.

MAURICE E. BATES.
